UNITED STATES PATENT OFFICE

CHARLES B. POST, OF NEW LONDON, OHIO

FLUTING MACHINE

Application filed April 15, 1931. Serial No. 530,222.

The objects of the invention are to provide automatically acting mechanism for pleating fabrics for attachment to gowns and for many other purposes.

5 By means of the improved mechanism the operations of pleating the fabric and sewing the pleats together can be swiftly performed, thus dispensing with the use of a large number of employees to perform the 10 same amount of work.

The invention includes the employment of endless belts or chains upon which the pleating teeth are secured in spaced relation to each other and operating means therefor, the 15 aforesaid teeth being provided with marginal recesses, which register with each other in overlapping teeth, thus providing supporting and guiding means for threaded needles that are transversely forced through 20 the pleats of fabric as fast as they are produced and can be afterwards withdrawn carrying the thread with them through the fabric.

The invention also includes a folding 25 frame, each portion of which carries one of said endless belts and which can be separated to permit the fabric and needles to be inserted between them.

The invention also includes tension means 30 for holding the rows of teeth in close relation to each other, means for detachably securing the needles in a central position between the belts upon which the teeth are mounted and guide means for the fabric 35 leading to a central position between said belts.

To accomplish these and other useful results, the invention includes the mechanism hereinafter described, illustrated in the accompanying drawings hereinafter more fully 40 described and particularly pointed out in the claims.

In the accompanying drawings Fig. 1 is 45 a front elevation of the device; Fig. 2 is an end elevation thereof; Fig. 3 is an elevation showing the endless belts and pleating teeth thereon, and the timing gears that give precision to the movements of the belts and teeth thereon; Fig. 4 is an enlarged plan of 50 the machine.

In these views A is a standard upon which the lower portion B of the frame is rigidly secured; C is the upper portion of the frame, which is hinged to the lower portion at the rear at D.

55 The two frames are provided at one end with the forwardly extending shaft bearings E and F respectively, in which the upper and lower shafts G and H are revolvable by means of the operating pulley or hand wheel I or other operating means, and spur gearing J and K respectively.

60 The teeth on these gears give precision to the movements of the belts.

65 At the front ends of these shafts, are secured the sprockets L and M upon which the flexible belts or chains N and O are mounted.

Upon the belts are secured the rows of 70 teeth P, P', which are regularly spaced to overlap and to alternate with each other, so as to produce the pleats in the fabric as it passes between them as shown in Fig. 3.

This action also feeds the fabric forward 75 between the teeth and forces the completed pleats over the needles Q, Q', which are threaded and pass entirely through the 80 pleats as fast as they are formed so that when withdrawn from the machine and the needles are withdrawn from the pleats the 85 pleats are sewed together.

To permit the needles to pass through the overlapping teeth and pleats the margins of the teeth are provided with recesses P², P'² through which the needles pass in turn as the 85 teeth revolve.

The needles are detachably inserted in openings P³ in the support R which is rigidly secured upon an extension R' of the frame, and a platform S receives the fabric and guides it to a central position between 90 the belts.

A spring T upon extensions T' T² of the frames maintains a pressure upon the teeth.

95 At the opposite end of the frame portions the sprocket wheels or idlers V, V', extend and support the respective belts and the idlers are mounted upon fixed projecting shafts W, W', that are secured to the projections W², W³ on the upper and lower frames respectively.

The machine thus constructed has many advantages in construction and use. It will operate successfully upon goods of any desired length. The flexible bands or chains carrying the overlapping teeth may be extended as far as may be desired and the needles being supported and guided closely in the recesses in a long succession of teeth may be made slender if desired, without danger of bending them under the pressure of the goods.

When in use, the action will be automatic, first to take in the goods, next to form the pleats or flutes, and to thread them over the needles and finally to feed the pleated goods over the needles throughout the desired length of the pleating.

The spur gears running in mesh with each other and by means of which accurate timing is obtained are desirable for general use, but if a more accurate form of pleating tooth is employed as for some particular work, the timing gears may be dispensed with.

The machines are adapted for use in fluting, pleating, ruffling or gathering, and are adapted to producing any form of fabrics in which the flutes or corrugations are held together by means of threads running centrally or nearly so through them.

One or more needles may be employed according to the character of the work and goods of one or more thicknesses may be pleated, several thicknesses being employed when it is desired to give the pleats or flutes a padded or puffed appearance.

These machines are ideal for the sewing machine type of power drive.

Having described the invention what I claim as new and desire to secure by Letters Patent is:

1. An automatically acting fluting machine, comprising a main frame, a pair of longitudinally spaced shafts therein, an upper frame pivoted to said main frame, at one side thereof, a pair of spaced shafts in said upper frame parallel with the shafts in said main frame, pulleys on said shafts, and upper and lower endless flexible toothed fluting members connecting the pulleys on each respective pair of shafts, the teeth on one flexible member intermeshing in turn with the teeth on the other flexible member, a needle support in line with the common pitch center of said flexible fluting members, and needles on said support, the intermeshing teeth of said endless flexible fluting members being provided with marginal guide openings in which said needles are supported throughout the fabric covered portion thereof, to prevent buckling thereof.

2. An automatically acting fluting machine, comprising a main frame, a pair of longitudinally spaced shafts therein, an upper frame pivoted to said main frame at one side thereof, a pair of spaced shafts in said

upper frame parallel with the shafts in said main frame, pulleys on said shafts, and upper and lower endless flexible toothed fluting members connecting the pulleys on each respective pair of shafts, the teeth on one flexible member intermeshing in turn with the teeth on the other flexible member, a needle support in line with the common pitch center of said flexible fluting members, and needles on said support, the intermeshing teeth of said endless flexible fluting members being provided with marginal guide openings, in which said needles are supported throughout the fabric covered portion thereof, to prevent buckling thereof, and resilient means for depressing said pivoted frame to exert vertical pressure upon both ends of said flexible fluting members, and upon the intermediate portions thereof, and to clamp said needles between said chains.

3. In a fluting machine in combination, a pair of spaced upper shafts, and a pair of parallel equally spaced lower shafts, an endless flexible chain connecting each pair of shafts, said chains being provided with intermeshing teeth, a fixed support and bearings for the lower pair of shafts, a common pivoted support and bearings for the upper pair of shafts, and means for exerting pressure upon said common pivoted support, needles passing between said chains at the pitch line of said teeth, said teeth on said chains being provided with marginal recesses for the reception of said needles, said pressure being equally distributed over said chains and needles.

4. In a fluting machine, a pair of parallel endless toothed chains and operating shafts therefor, the teeth on one chain intermeshing in turn with the teeth on the other chain said teeth being provided with marginal recesses, a rigid needle support at one end of said machine, and a needle extending through the common pitch line of said endless chains, and rigidly supported in said marginal recesses therein, and means for exerting uniform pressure upon the entire length of the upper chain and needle.

5. In a fluting machine, a pair of upper and lower parallel endless toothed chains and operating shafts therefor, the teeth on one chain intermeshing in turn with the teeth on the other chain said teeth being provided with marginal recesses, a rigid needle and a support therefor at one end of said machine, said needle extending through the common pitch line of said endless chains and rigidly supported in said marginal recesses therebetween, and means for exerting uniform pressure upon the entire length of said upper chain, and means for giving regularity of movement to said needle supporting chains.

In testimony whereof I affix my signature.

CHARLES B. POST.
